(57) **CLAIM**

The ornamental design for a dog vest harness as shown and described.

DESCRIPTION

FIG. 1 is a left side elevation view of a dog vest harness showing my new design;

FIG. 2 is a right side elevation view thereof;

FIG. 3 is a top plan view thereof;

FIG. 4 is a bottom plan view thereof;

FIG. 5 is a front elevation view thereof;

FIG. 6 is a rear elevation view thereof; and,

FIG. 7 is a bottom plan view, showing the dog vest harness in an alternate, flat configuration.

The claimed design shows a contrast of materials by using line shading in one area, overlapping arcs in another, and overlapping scribbles in another.

The broken lines on the dog vest harness depict stitch lines and form no part of the claimed design.
